UNITED STATES PATENT OFFICE.

CLARENCE A. MICHEL, OF CLEVELAND, OHIO, ASSIGNEE TO THE GUIDE MOTOR LAMP MANUFACTURING COMPANY, OF CLEVELAND, OHIO, A CORPORATION OF OHIO.

AUTOMOBILE HEADLIGHT.

Application filed February 13, 1925. Serial No. 8,881.

This invention relates generally to automobile headlights and more particularly to certain improvements pertaining to the lamp and reflector whereby the driving conditions 5 are improved.

In most automobile headlights as at present constructed a single filament lamp is arranged centrally of the reflector and a single filament lamp usually of less candle power is arranged 10 near the top of the reflector. The central lamp is used for road driving while the upper lamp is used for city driving and when passing other automobiles upon the road.

Furthermore, in automobile headlights as 15 at present constructed it is common to employ a modified form of reflector or a modified form of lens with the idea of preventing the disagreeable glare when meeting other automobiles or pedestrians. These improvements 20 are serviceable at times and there are other times due either to the unevenness of the road or the movement of the automobile that they are not serviceable.

The object of my invention is to add an element of safety to the present devices by employing a double filament lamp which is centrally arranged and in combination with a reflector so constructed that the top of the beam is projected forwardly within the legal limit a 25 considerable distance in advance of the automobile for road driving and for city driving or while passing other automobiles the top of the beam can be materially deflected or drawn downwardly so as to avoid all possibility of 30 glare. In order to further safeguard the matter I may use one of several types of refracting lenses in combination with the double filament lamp and modified reflector.

In the drawings forming a part of this specification I have shown one embodiment of my invention and in which Fig. 1 is a vertical sectional view of a reflector and lamp constructed and arranged in accordance with my invention together with the lens arranged in advance of the reflector; Fig. 2 is a face view of the reflector; Fig. 3 is a face view of one form of lens which can be used in connection therewith.

In carrying out my invention I employ a lamp A having two independently lighted filaments B and C, the filament B being arranged substantially on the axis D of the reflector E and the filament C is arranged a very short distance below the filament B. The upper and lower halves of the reflector are of different focal lengths, the focal points being spaced

apart, the focal point of the upper half being arranged at the rear and the focal point of the lower half being arranged forward of the filaments, that is to say, the filaments are arranged substantially between the two focal 60 points.

The upper half of the reflector is indicated at F and the focal point thereof at F' and the focal point of the section G is located at G'. The lower portion of the lower half is of the 65 same curvature of revolution as the portion G but is tilted downwardly approximately two degrees as indicated by the dotted line H'. This insures the downward reflection of the rays from either filament. 70

In order to avoid formation of sharp angles by the intersection of curvatures of revolutions of different focal lengths and also to facilitate the manufacture of the one-piece reflector, I provide transition surfaces between 75 the sections F and G as most clearly indicated at M.

The lower filament C is the filament employed for ordinary road driving and the top of the beam is projected a considerable distance in advance of the automobile. When, however, the lower filament is extinguished and the upper one lighted the rays of light will be perceptibly lowered, it being understood, however, that when the lower filament is employed all of the rays of light are directed either horizontally or below the horizontal but when the upper filament is employed all of the rays are perceptibly depressed. 85

In order to give lateral distribution I propose to employ a lens L having vertical flutes L' of uniform size and completely covering the face of the lens. This form of lens is shown in Fig. 3. Other types of lenses can be employed in case further lateral distribution 95 or additional vertical deflection of the rays of light should be desired.

It will thus be seen that I provide a novel construction of reflector in combination with a double filament lamp with the filaments arranged to produce the results desired. 100

Having thus described my invention, what I claim is:—

1. In a light projector, the combination with a reflector, of a lamp having two independently lighted filaments one of said filaments being located on the axis of the reflector and the other one below said axis, the upper and lower halves of said reflector having different focal lengths, the focus of the upper 110

half of the reflector being at the rear of the filaments and the focus of the lower half of the reflector in front of said filaments, the filaments being located intermediate the focal points, the lower portion of the lower half of said reflector being tilted downwardly whereby rays of light from either filament will be reflected downwardly.

2. In a light projector, the combination of a reflector and a lamp having two independently lighted filaments one of said filaments being located on the axis of the reflector and the other filament below the said axis, the upper

and lower halves of said reflector having different focal lengths the focal point of the lower half being in advance of the focal point of the upper half, the filaments being located intermediate the focal points, the lower portion of the lower half of the reflector being tilted downwardly whereby rays of light from either filament will be reflected downwardly, and transition surfaces interposed between the upper and lower halves of the reflector.

In testimony whereof, I hereunto affix my signature.

CLARENCE A. MICHEL.
